UNITED STATES PATENT OFFICE

2,579,323

ROCKET PROJECTILE

Gregory J. Kessenich, Madison, Wis., assignor of one-sixth to Pauline C. Kessenich, one-sixth to William H. Kessenich, one-sixth to Rose Mary C. Kessenich, one-sixth to Thomas G. Kessenich, and one-sixth to Christopher J. Kessenich, the shares of Thomas G. Kessenich and Christopher J. Kessenich, minors, to be held in trust for their benefit by the co-owners

Application February 14, 1944, Serial No. 522,293

3 Claims. (Cl. 102—49)

1

This invention relates to a projectile for a firearm and particularly to a rocket projectile capable of carrying a large charge of explosive, which may be transported and fired by one man.

Modern warfare has demonstrated the need for a weapon of great destructive properties which may nevertheless be transported and operated by an individual soldier. This is particularly true of infantrymen who are opposed by tanks or other armored vehicles or who must reduce fortified positions without supporting artillery. To destroy such vehicles or positions requires a substantial quantity of explosive charge which generally requires a projectile of at least several inches in diameter. To fire a projectile of such size, of course, requires an artillery piece of a size much in excess of that transportable by an individual soldier. Hence prior to this invention the individual soldier had to depend upon hand thrown grenades or other types of bombs which, of course, required that he be so close to the enemy target as to render his position very precarious.

Rifle grenades have heretofore been used with effectiveness but whether projected by gases from a blank cartridge or by-passed gases from a live round their range is not great especially where the grenade is of some weight. Further, maximum range has only been obtained by high angle firing and as a consequence of the inherent inaccuracy the rifle grenade was not suited for firing at high speed targets. Attempts to increase the weight of the rifle grenade have resulted in decreased range, ballistic inaccuracy and in causing damage and breakage of the rifles.

With a view to obviating these disadvantages it is proposed in this invention to provide an improved projectile having great destructive properties which may be launched as a rocket from a projector capable of being transported and fired by an individual soldier. The projectile may be initially launched as a rocket or it may receive initial impulsion by a mechanical source or by the gases passing thru the bore of a firearm, the initial impulsion means being utilized to ignite the rocket charge. A low trajectory projectile is thus obtained which will present more favorable angles of impact and which will permit eye-aiming of a shoulder piece at a rapidly moving target.

The specific nature of the invention as well as other objects and advantages thereof will clearly appear from a description of a preferred embodiment as shown in the accompanying drawings wherein there is shown a rocket projectile in longitudinal section embodying this invention.

2

In the drawing there is shown a projectile embodying this invention. The projectile comprises a hollow cylindrical body 1 on the rear end of which is secured a plurality of projecting fins 2 which serve to stabilize the projectile in flight. The forward end of body 1 is threadably secured to a second hollow cylindrical body 20. The rear end of body 20 is provided with an integral partition 21 which has an integral raised boss 18 centrally provided thereon. Parts 1 and 20 when united as shown, form a body portion or casing. An impact fuse 3 of any well known type is axially mounted in a suitable recess 23 in the boss 18. A disk 4 of suitable heat insulating material is placed adjacent the rear side of partition 21 and is held in such position by body 1 when such body is threaded into the second cylindrical body 20 as shown in the accompanying drawing.

A rocket propulsion charge 5 is mounted within 20 the interior of the hollow body portion 1. While such charge may comprise any one of various well known arrangements of powder charges, it is here shown as comprising a compacted mass of powder grains pressed into the hollow body portion, preferably around a long conical arbor (not shown) so as to define a central conical recess 6 extending into charge 5. The gases developed by ignition of powder charge 5 exhaust thru a nozzle 7 provided on the extreme rear end of body 1. Nozzle 7 is preferably of conventional Venturi construction and effectively produces a gas blast, the reaction force of which acts as a propellant force for the projectile.

Powder grains 5 are ignited by an ignition 35 charge 8 of black powder. The ignition charge 8 is contained within a cup 9 mounted in the ori- 40 fice of nozzle 7. The powder 8 is retained within cup 9 by a thin disk 10 of combustible material cemented to the top of such cup. Ignition of charge 8 is effected by a conventional small arms primer 11. The cup 9 is fitted into nozzle 7 in such manner that the gas pressure developed after ignition of propellant charge 5 will forcibly eject cup 9 from nozzle 7.

An ogival nose 13 is mounted on the forward 45 end of body 1. The nose 13 is preferably formed from thin sheet metal so that it will readily collapse upon impact with the target. The forward chamber in body 20 defined between partition 21 and ogive 13 is arranged to receive an explosive 50 charge constructed similar to that disclosed in British Patent No. 28,030 of 1911 which has a cavity in its front face and a liner of rigid material fitting the cavity and retaining the explosive charge. Such an arrangement comprises 55 an explosive charge 14 packed into the forward

chamber behind a partition or liner 15 extending between the walls of body 20 and formed as a reentrant surface having its central portion rearwardly disposed with respect to its edges. In accordance with the teaching of the aforementioned British patent the partition 15 is preferably conically shaped but may be spherical, prismatic, or cylindrical. The main requirement is that a cavity 16 be produced in the front of explosive charge 14, the reentrant surface of the explosive receiving and fitting the reentrant surface of the liner 15 as shown in the drawing.

The explosive charge 14 is arranged to be detonated by the fuse 3 which may be one of several well known types of impact fuses and need not be further described. A primer 17 is mounted in such fuse and is arranged to be set off by the inertia forces arising out of the impact of the projectile on the target. Preferably the fuse 3 will be adjusted to operate at or before the instant when the ogive 13 has collapsed back to a point where it is flush with the end of body 20. Under this condition there is still a substantial cavity 16 in front of explosive charge 14 and accordingly the great explosive effect produced by the arrangement of the above cited British patent will be obtained.

This improved projectile may be launched in any of a number of well known rocket launchers of a type shown in a book entitled "Ammunition" published by the British Government in 1870. The launcher may be a hollow tube open at both ends plus some conventional form of firing mechanism to strike or ignite primer 11. The hollow tube is utilized to aim the rocket projectile and launch it airborne and since it is open at both ends there will be little, if any, recoil force exerted upon the tube and hence the tube may be readily held and eye-aimed as a shoulder piece by an individual soldier to launch this projectile as well as a companion round described in my concurrently filed application, Serial No. 522,292, now Patent No. 2,494,562. Furthermore the entire apparatus, both launcher and projector, are light enough to be carried by one man. At the same time the great explosive effect produced on the target by this type of projectile is equivalent to that produced by artillery of substantial caliber.

The combination of the arrangement of the explosive charge disclosed in the above cited patent with a rocket type projectile is particularly advantageous since the particular arrangement of the explosive charge does not require penetration of the target for maximum effectiveness and further because the low velocity of impact of the rocket type projectile coupled with the collapsing of the ogive 13 insures that the projectile will remain in contact with the target long enough to accomplish the full ignition of the explosive charge 14. Furthermore, due to the generation of propulsion force during flight, an

usually flat trajectory may be obtained at the relatively slow velocity of the projectile. Hence the aiming of the projector by eye is quite feasible and the rocket projectile may be accurately directed at many targets.

I claim:

1. In a projectile for a shoulder-fired rocket projector, a smooth, generally cylindrical rocket casing having its rear portion tapering to a rearwardly-directed nozzle and a forward reduced externally threaded neck, a cylindrical explosive container having its rear end wall internally threaded to engage the threads of said neck to unite said casings into a continuous smooth-walled cylindrical projectile, a transverse wall integral with said explosive container immediately forwardly of the internal threads thereof, a thin-walled hollow ogival nose section attached to and closing the forward end of said explosive container, said nose having a conical re-entrant portion extending into said explosive container and forming therewith a closed chamber, an explosive charge filling said chamber, a disc of heat-insulating material having its rim clamped between said wall and the threaded neck of said rocket casing, and an impact fuze having an enlarged head clamped between said wall and disc and a reduced body portion extending through an aperture in said wall into said explosive charge.

2. In an aerial missile, a rocket, airfoil means on the rocket to control it in fin-stabilized flight, an explosive charge carried at the front of the rocket, said charge having a cavity in its forward end and operable on impact, and a liner of rigid material fitting in the cavity of the explosive charge.

3. In an aerial missile, a rocket, airfoil means on the rocket to control it in fin-stabilized flight, an explosive charge carried by said rocket forwardly thereof, said explosive charge having a forwardly-divergent recess opening through the forward end thereof, a liner of rigid material fitting said recess, an ogival nose forwardly of the liner and spaced therefrom and a fuze carried by said rocket in detonating relation with said explosive charge.

GREGORY J. KESSENICH.
